(57) **CLAIM**

The ornamental design for a shower system, as shown and described.

DESCRIPTION

FIG. 1 is a perspective view of a shower system of the present design;

FIG. 2 is a perspective view of a shower of the present design;

FIG. 3 is a front view of the shower thereof and the back view not shown in FIGs;

FIG. 4 is a left side view of the shower thereof and the right side view and the left side view are symmetrical design;

FIG. 5 is a top view of the shower thereof;

FIG. 6 is a bottom view of the shower thereof;

FIG. 7 is another perspective view of the shower thereof;

FIG. 8 is a perspective view of a handle of the present design;

FIG. 9 is a front view of the handle thereof and the back view not shown in FIGs;

FIG. 10 is a left side view of a handle thereof and the right side view and the left side view are symmetrical design;

FIG. 11 is a top view of the handle thereof;

FIG. 12 is a bottom view of the handle thereof;

FIG. 13 is another perspective view of the handle thereof;

FIG. 14 is a perspective view of a faucet of the present design;

FIG. 15 is a front view of the faucet thereof and back view not shown in FIGs;

FIG. 16 is a left side view of the faucet thereof and the right side view and the left side view are symmetrical design;

FIG. 17 is a top view of the faucet thereof;

FIG. 18 is a bottom view of the faucet thereof;

FIG. 19 is another perspective view of the faucet thereof; and,

FIG. 20 is a perspective view shown the using status of the shower system of present design.

The broken lines used in FIG. 20 show the environment where the shower system is used and define the bounds of the claimed design and form no part thereof.

1 Claim, 15 Drawing Sheets
